UNITED STATES PATENT OFFICE.

PIERRE HOYOUX, OF ROCHESTER, PENNSYLVANIA.

CATCHING-OFF MACHINE.

Application filed June 20, 1923. Serial No. 646,690.

To all whom it may concern:

Be it known that I, PIERRE HOYOUX, a citizen of the United States, residing at Rochester, in the county of Beaver and 5 State of Pennsylvania, have invented new and useful Improvements in Catching-Off Machines, of which the following is a specification.

The primary object of this invention is 10 to provide means for handling goblets as they come from the finisher so as to render it unnecessary to employ "carrying in" boys, thus reducing the labor expense and producing goblets at a low cost.

15 Another object of the invention is to make the parts adjustable so that they can be used on goblets of different sizes and of different weights.

This invention also consists in certain 20 other features of construction and in the combination and arrangement of the several parts, to be hereinafter fully described, illustrated in the accompanying drawings and specifically pointed out in the appended 25 claims.

In describing my invention in detail, reference will be had to the accompanying drawings wherein like characters denote like or corresponding parts throughout the 30 several views, and in which:

Fig. 1 is a side view with the parts in horizontal position.

Fig. 2 is a similar view with the parts in vertical position.

35 Fig. 3 is an edge view of Fig. 1.

Fig. 4 is an end view of Fig. 1, looking from the opposite end shown by Fig. 3.

Fig. 5 is a detail sectional view through the cross-bar showing a portion of one of 40 the upright rods carried thereby.

Fig. 6 is a section on line 6—6 of Fig. 1.

In these views 1 indicates a base which supports a post 2 to the upper end of which an angle bracket 3 is secured. The vertical 45 arm of this bracket is forked to receive a cross bar 4 which is pivoted to the bracket by the pivot 5, a portion of the pivot being extended and bent at right angles, as at 6, to receive a weight 7 which is adjustably 50 connected thereto. This weight tends to hold the cross bar in horizontal position. Upright rods 8 and 9 are slidably mounted on the cross bars and are held in adjusted position thereon by the clamping bolts 10. 55 A screw shaft 11 engages a screw threaded hole in the base of each upright rod, so

that when the shafts are turned the rods can be adjusted towards and away from each other. The shafts are carried by the end pieces 12 on the cross piece 4. These 60 shafts have handles 13 formed on their outer ends so that they can be turned by hand. Each rod carries substantially U-shaped holders 14 and 14' at their upper ends which are preferably formed of asbestos, the holder 14', carried by the rod 8, has a hinged section 15 which is normally held in lowered position by a spring 16 so that the top of the goblet can be placed therein. The other holder is stationary as 70 its opening is large enough to receive the stem of the goblet.

The goblets as they come from the finisher are placed in the device while the parts are in a horizontal position, as shown 75 in Fig. 1. The unfinished top of the goblet is cracked off and then the cross bar 4 with the parts carried thereby will slowly turn to a vertical position with the holders supporting the goblet without weight on the 80 stem. Thus this device will eliminate the use of a boy to hold the goblet in a fork until the finisher cracks the top therefrom and it is passed to the leers. As two of these boys are used to each goblet shop it 85 will be seen that this device will reduce the labor expense.

The parts are adjustable to suit goblets of different sizes and weights and the adjustable weight permits the device to be 90 balanced so that it will drop to a vertical position as soon as the unfinished top of the goblet is cracked off. As soon as the goblet cools sufficiently it is removed from the device and sent to the leers. 95

It is thought from the foregoing description that the advantages and novel features of my invention will be readily apparent.

I desire it to be understood that I may make changes in the construction and in the 100 combination and arrangement of the several parts, provided that such changes fall within the scope of the appended claims.

What I claim is:

1. A device of the class described comprising a supporting stand, a frame tiltably supported thereon, an adjustable weight for balancing the frame in a horizontal position, a pair of holders adjustably arranged on the frame and means permitting one of 110 the holders to be opened to admit the top of the goblet.

2. A device of the class described comprising a supporting stand, a cross bar pivotally arranged therein, an adjustable weight for holding the cross bar in horizontal position, a pair of uprights slidably arranged on the cross bar, screw shafts for adjusting the uprights towards and away from each other, a holder carried by each

upright, each holder being of substantially U-shape and one holder having a movable part for permitting the top of a goblet to be inserted therein. 10

In testimony whereof I affix my signature.

PIERRE HOYOUX.
